Inventor

John Neff, Jr.

United States Patent Office.

JOHN NEFF, JR., OF PULTNEY, NEW YORK.

Letters Patent No. 64,692, dated May 14, 1867.

PRUNING-SHEARS.

The Schedule referred to in these Letters Patent and making part of the same.

TO ALL WHOM IT MAY CONCERN:

Be it known that I, JOHN NEFF, Jr., of Pultney, in the county of Steuben, and State of New York, have invented a new and useful Improvement in Pruning-Shears; and I do hereby declare that the following is a full, clear, and exact description of the construction and operation of the same, reference being had to the annexed drawing, making a part of this specification, in which the figure is a side view of the whole improvement.

The nature of my invention consists in making pruning-shears with one spring, and a lever to hold them open and not have them press so hard against the hand when closed as when open, and having the spring much shorter than those of ordinary pruning-shears, thereby avoiding the liability of breaking springs.

To enable others skilled in the art to make and use my invention, I will proceed to describe its mode of construction and operation.

A is one of the parts; it constitutes the cutting-blade and the handle, as shown in the figure. To this handle the spring F is fastened by a screw or rivet; also the catch G is pivoted at the end of the handle. The blade may be made any shape required, and the edge may be made sharp, for it is required to do the cutting. B is the other part; its blade is in shape to correspond with the blade A, and has no cutting-edge. To the handle the spring D and lever C are fastened, as shown in the figure. Both handles may be made any shape that will please the fancy and hold the other parts specified. C is a lever; it may be made in the shape represented in the figure, or in shape to correspond with other shaped handles. One end is held in the mortise in the end of the handle by a pivot so as to move freely. The other end is provided with a roller, when desired, or it may be made without the roller and perform its office satisfactorily; this end may be fitted to the handle of A to produce the required results; its length may be varied to produce different effect in opening the handles. This lever and the spring D may be applied to the other handle with the same result, if desired. D is the spring that causes the shears to open; it is made of a plane piece of steel slightly curved, as shown in the figure. One end is held to the handle of B by a screw. The spring may be curved so that with the screw the power of the spring may be increased or diminished at will. The other end bears upon the lever C and thus causes the shears to open. E is a roller, fitted to the end of the lever C'; its use is to prevent friction and wear at the end of the lever; it is made to move in a groove in the handle of the part A, as represented by the dotted line in the figure. F is a small spring, fastened to the handle of the part A, as shown in the figure; its use is to hold the catch G in any required position. G is a catch that is used to hold the shears closed when not in use; it is pivoted into a place fitted for it in the handle of the part A, as shown in the figure.

Having thus fully described my invention, what I claim as new, and desire to secure by Letters Patent, is—
I claim the lever C and spring D, when made and arranged substantially as specified and used for the purpose set forth.

JOHN NEFF, JR.
